M. L. PETTES.
MATTRESS HANDLE.
APPLICATION FILED JAN. 22, 1914.

Patented Feb. 8, 1916.

UNITED STATES PATENT OFFICE.

MARY L. PETTES, OF LAKOTA, NORTH DAKOTA.

MATTRESS-HANDLE.

1,170,844.

Specification of Letters Patent.

Patented Feb. 8, 1916.

Application filed January 22, 1914. Serial No. 813,732.

To all whom it may concern:

Be it known that I, MARY L. PETTES, a citizen of the United States, residing at Lakota, in the county of Nelson, State of North Dakota, have invented certain new and useful Improvements in Mattress-Handles; and I do hereby declare the following to be a full, clear, and exact description of the invention, such as will enable others skilled in the art to which it appertains to make and use the same.

This invention relates to improvements in mattresses, and particularly to a handle therefor.

One object of the invention is to provide handles for the sides and ends of a mattress so that the mattress may be conveniently lifted and carried in either a flat or folded position.

Another object is to provide handles for a mattress which are readily adjustable to mattresses of different widths.

A further object is to provide handles which may be readily attached to or detached from the binding edges of the mattress.

Other objects and advantages will be apparent from the following description, when taken in connection with the accompanying drawings.

In the accompanying drawings: Figure 1 is a perspective view of one corner of a mattress illustrating the use of my handles. Fig. 2 is an enlarged elevation of one of the handles detached. Fig. 3 is a vertical section on the line 3—3 of Fig. 1. Fig. 4 is a view similar to Fig. 3 showing the handle attached to a thinner mattress.

Referring particularly to the accompanying drawings, 10 represents the body of the mattress, 11 the vertical webbing between the top and bottom thereof, and 12 the binding strips which project from the sides and ends of the mattress. My handles are par-

ticularly adapted for attachment to these 45 binding strips.

Referring to my handle in detail, and as particularly illustrated in the drawing, the same comprises the two rectangular wire frames 13, the outer longer sides of which 50 are provided with suitable fasteners 14 for attachment respectively to the upper and lower binding strips 12. The other long sides of these frames 13 are twisted together throughout their lengths as clearly indicated at 15. This twisted portion of the device forms a hand grip, and also acts as a hinge. As a hinge the frames 13 may be swung toward or away from each other so that they can be readily attached to the binding strips of mattresses of different thicknesses. While I have shown the fasteners 55 14 in the semblance of ordinary safety pins, I wish it understood that I may use any other fasteners to attach the handle to the 60 mattress without deviating from the spirit 65 or scope of the claim.

What is claimed is:

A detachable handle for a mattress comprising a pair of elongated closed frames, 70 one of the longer sides of one of the frames being intertwined with one of the longer sides of the other frame, and fastening devices movably carried by the other longer sides of the frames for detachably movable 75 attachment to the binding edges of a mattress, said twisting portion serving the double function of a hand grip and as a hinge for the frames whereby the device can be attached to mattresses of different thicknesses. 80

In testimony whereof, I affix my signature, in the presence of two witnesses.

MARY L. PETTES.

Witnesses:

GEO. A. KELLOGG,
CHAS. R. PETTES.
